(57) **CLAIM**

The ornamental design for a Louis XVI style table, as shown
and described.

DESCRIPTION

FIG. 1 is a front perspective view of a Louis XVI style table
embodying my new design with a first playing surface on the
top of the table;

FIG. 2 is a front perspective view of a Louis XVI style table
embodying my new design with a second playing surface
rotated to the top of the table;

FIG. 3 is a front elevational view thereof;

FIG. 4 is a rear elevational view thereof;

FIG. 5 is a left side elevational view thereof, and the right
side elevational view being a mirror image thereof;

FIG. 6 is a top plan view thereof; and,

FIG. 7 is a bottom plan view thereof.
